ELECTRIC CONTROL APPARATUS

Harold F. Elliott, San Francisco, Calif.

Original application July 16, 1940, Serial No. 345,762. Divided and this application July 22, 1946, Serial No. 685,410

17 Claims. (Cl. 74—10.2)

1

This invention relates to control apparatus and in particular to an automatic tuning system for radio receiving apparatus. It is a division of applicant's Patent No. 2,411,617, issued November 26, 1946, and is also related to copending application Serial No. 688,920, filed August 7, 1946, a continuation of copending application Serial No. 424,234, filed December 24, 1941, now abandoned.

It is an object of this invention to provide an improved automatic tuning system for radio receiving apparatus.

A further object of this invention is to provide a physically compact tuning device, which is simple, inexpensive, efficient in operation and of preassembled unit construction.

Yet another object of this invention is to provide control apparatus in which a plurality of rotary control units for driving a rotary control shaft, are selectively operated by a common driving means.

Another object of this invention is to provide an electrical tuning system in which each of a plurality of control units for driving a rotary control shaft in operative engagement with frequency-changing means, is constructed to move the frequency-changing means through its entire tuning range with a relatively low driving ratio to effect a precision tuning thereof.

A feature of this invention is the provision of electrical tuning apparatus embodying rotary operating members in which actuating magnets are utilized to provide a trip action for mechanically engaging the operating members, such members being arranged to be self-engaging after their initial engagement. Small magnets may thus be efficiently used whereby to appreciably reduce the cost of the tuning apparatus.

Another feature of this invention is the provision of electrical tuning apparatus in which the actuating magnets are equally efficient in either A. C. or D. C. systems without the necessity of changing the pole structures thereof; the structure operated by the magnets being assembled in a manner to eliminate the usual chattering action of the unshaded magnets when used in an A. C. system. Similar magnets may thus be used for both types of systems whereby to further reduce the cost of the tuning apparatus.

Yet another feature of this invention is found in the provision of a tuning unit in which the operating parts are arranged to form an integral part of the frame means for the unit.

A still further feature of this invention is the provision of tuning apparatus having a plurality of rotary control units operably engageable with

5 a common driving member through magnetically actuated clutch means, in which the magnets and driving motor for the common driving member are concurrently energized by selectively actuated push buttons located remotely from the tuning apparatus.

Another feature of this invention is the provision of a tuning device in which a manually actuated clutch unit for connecting a rotary control unit with a motor driven driving member is arranged to close the energizing circuit of the motor after its clutching operation, whereby to immediately operate the control unit.

Yet another feature of this invention is the provision of control apparatus in which a rotary control shaft is rotated in either direction of rotation by a rotary control unit operated by a unidirectional motor.

Further objects, features, and advantages of 20 this invention will become apparent from the following specification when taken in connection with the accompanying drawings, in which:

Fig. 1 is a plan view of one embodiment of the invention with parts thereof broken away for the 25 purpose of clarity;

Fig. 2 is an end elevational view looking toward the right as viewed in Fig. 1, with parts thereof broken away to show the driving system for the rotary control means;

Fig. 3 is a fragmentary bottom view showing the frequency-changing means and its driving engagement with the rotary control means;

Fig. 4 is a fragmentary bottom view of the driving motor and its associated clutch assembly;

Fig. 5 is a fragmentary detailed sectional view of the driving end of the motor shaft;

Fig. 6 is a detail view, partly in section, of the gear train for the rotary control units. This detail is illustrated as removed from the structure of Fig. 1 and rotated toward the reader sufficiently to show the shaft and gear relationship more clearly;

Fig. 7 is a sectional view of the rotary control means showing the arrangement thereon of the 40 rotary control units; while,

Fig. 8 shows an electric control circuit for the embodiment of Fig. 1.

Referring to the drawings, the preselector unit shown in Figs. 1, 3, and 4, is seen to include frame means having end plates 21 and 22, spaced apart by lower tie rods 23 and an upper tie rod 24. A unidirectional driving motor 26 is mounted on the end plate 21 by supporting studs extended through the laminated motor field structure 27. The motor is positioned away

from plate 21 by spacers 28 and secured in place by nuts 29. End 31 of the motor shaft 32 projects through the plate 21 and has mounted thereon a clutch assembly 33, which includes a steel washer 34, a spring washer 36, a pinion gear 37, a fibre friction washer 38 and an assembly retaining bushing 39. The shaft end 31, as clearly shown in Fig. 5, is of reduced section and is formed with a flat portion 41 near the outer extremity thereof. The shoulder portion 42 serves as a stop or abutment for the washer 34 to define the inner position of the clutch assembly 33, with the flat portion 41 frictionally engaging the set screw 40 of the retaining bushing 39 to positively maintain the clutch assembly 33 on the motor shaft 32. Gear 37 is in driven engagement with a gear 43 which is mounted at one end of a supporting shaft 45 for an elongated pinion gear 44 (Figs. 1 and 2). It is contemplated that gear 43 be of fibre or other like composition material. Gear 43 rotates the shaft 45 through a spring connection with a retaining bushing 46. The looped end 47 of the coil spring 50 is connected to a friction screw 48 (Fig. 1) which holds the bushing 46 in a fixed position relative to the pinion shaft 45. The opposite end 49 of the spring is hooked into an aperture 51 formed in the face of the gear 43. The spring connection of the gear 43 to the bushing 46 thus provides a flexible drive between the motor shaft 32 and the pinion-gear shaft 45 and prevents any possible "freezing" together of the power-transmitting gears 117 and 44 as will be explained later. A steel washer 52 holds the gear 44 loosely upon hub 46 so that it is free to rotate relative to the hub within the limit imposed by spring 50.

The elongated pinion gear 44 is arranged for driving engagement with gear trains 53, one of which is provided for driving each of the rotary control units 54. The units 54 are mounted on a rotary control shaft 57 which is rotatably supported in the end plates 21 and 22. A gear 58 mounted on the shaft 57 near its end 59 is in operative engagement with a condenser gear 61 which is mounted on the condenser shaft 62 (Figs. 1 and 3). The condenser 63 is supported on the end plate 22 by suitable screw means 64 or the like. Although the condenser 63 is illustrated as being a gang condenser, it is to be understood that other frequency-changing means may be used with equal satisfaction. The motor 26 is thus seen to be in driven engagement with the condenser 63 through the mechanism above described, the extent of condenser rotation for tuning purposes being controlled by rotation of the control shaft 57 in a manner now to be described.

The control units 54 are similarly constructed and are mounted in succession axially of the control shaft 57 (Figs. 1 and 7). Each unit includes a pair of similar gears 65 and 65' mounted on similar bushings 66 and 67 having annularly extending shoulder portions 68. The bushings are broached on the inside thereof in conformance with the flats 69 formed on the control shaft 57, so as to be keyed to the shaft. Gear 65 and washers 71, three in number, are freely rotatable on the bushing 66; and gear 65' and washers 72, also three in number, are freely rotatable on the bushing 67. The washers 71 and 72 are similar, the projections 73 and 74, respectively, formed thereon extending axially toward each other. The projections 73 and 74

are of a length somewhat less than the thickness of the washers 71 and 72 so that the projections on adjacent washers only are engageable. Thus on rotation of gear 65 the projection 76 integrally formed thereon engages the projection 73 on the next adjacent washer 71, with the projections or fingers 73 on the remaining washers 71 being successively engaged on continued rotation of the gear 65 until a coupled engagement of the gear 65 is made with the radially extending projection 77 formed on a center washer or adjustable collar member 78 arranged between the bushings 66 and 67. Rotation of gear 65' provides for a similar operation of the washers 72 into engagement with the projection 77, for a purpose to be later explained. The member 78 is normally freely rotatable on the control shaft 57, so as to be adjustable with a predetermined position in correspondence with a particular control position of the shaft. The adjusted position of the member 78 is maintained by its frictional engagement with the adjacent ends of the bushings 66 and 67, as will be explained. The coupled engagement of both gears 65 and 65' through their respective washers 71 and 72 with the adjustable collar member 78, defines the predetermined control position of the shaft, 57, as will be later fully explained.

As shown best in Fig. 7, the portion of the control shaft 57 carrying the pinion gear 58 is of enlarged section to form a shoulder 79 on the shaft. A spacing member 81 keyed to the shaft 57 and pressed against the shoulder 79 positions the control units 54 and gear 58 away from the end plate 22 while a similar unit 82 spaces the control units and a clamping unit 88 away from the end plate 21. In assembly, therefore, the spacers 81 and 82 and units 54 are mounted on the reduced section of the shaft 57 and strung over the length thereof in a proper assembly order prior to the positioning of the shaft in the end plates 21 and 22. Conditioning of the units 54 to provide for a predetermined positioning of the center washers 78 relative to the shaft 57 is accomplished by the two washers 83 and 84 which have a spring washer 86 located therebetween. On separation of the washers 83 and 84, the spring is released until the control members 78 for each of the units 54 are permitted to rotate under but slight pressure from the spring 86 on the shaft 57, so as to be freely movable to an adjusted position, as will be explained. On a clamping together of the washers 83 and 84, the bushings 66 and 67 in each control unit are frictionally pressed toward each other to engage opposite sides of the member 78, whereby to clamp the member in the position which it has at the time of such engagement. The clamping action of the washers 83 and 84 is controlled by manipulation of a set screw 87 (Figs. 1 and 7) which is positioned in the thrust member or clamp 88. By virtue of the engagement of pin 89 in the tapered slot 91 formed in the member 88, adjustment of the set screw 87 acts to move the member 88 away from or toward the control units 54 to control the action of the washers 83 and 84 on the spring 86 in a manner which is clearly apparent.

The gears 65 and 65' are engageable with pinions 92 and 93, respectively, which are included in each of the gear trains 53 for the units 54. The pinions 92 and 93 are engageable with each other and arranged so as to rotate the gears 65 and 65' in opposite directions on turn-

ing of either thereof. The pinions 92 are axially aligned and freely rotatable on a shaft 97; each pinion 92 (Figs. 1 and 6) is self-spacing and is formed with a spacer portion 94 and a toothed or gear portion 96, the portion 94 being of a length to position each of the toothed portions 96 substantially opposite a gear 65 for each of the control units 54. Assembly of the pinions on the shaft 97 is maintained by a bushing 98 which is frictionally engageable with the shaft through friction screw 99. The threaded ends of the shaft 97 are held by nuts 102 to tie plates 101 and extend through the frame end plates 21 and 22; the nuts 102 serving to hold the tie plates 101 against the pinion assembly and to space the pinions from the end plates 21 and 22. Nuts 103 on the outside of the end plates 21 and 22 fixedly mount the shaft 97 thereon.

The pinions 93 are substantially similar to the pinions 92 and are axially aligned and freely rotatable on a shaft 104 having threaded ends which are mounted in the tie plates 101 and the end plates 21 and 22 in a manner similar to that above described for the shaft 97. The spacer portions 95 are arranged substantially opposite the gear portions 96 of the pinions 92, and the gear portions 100 are substantially opposite the gears 65' and engageable therewith. The shafts 97 and 104 are thus seen to be parallel to each other, with the pinions 92 and 93 arranged substantially opposite a corresponding control unit 54 and in engagement with the gear members 65 and 65', respectively.

Interposed between adjacent pinions 92 is a rocker arm or armature 106 for each unit 54 which is of substantially L-shape and freely rotatable on the shaft 97. As shown in Figs. 1 and 2, the leg portion 107 of each armature is arranged in an attractable position relative to the pole 108 of a magnet 109. The attraction of the armature 106 by the magnet 109 is opposed by a spring 111 which is connected at one end to a projection 112 formed on the armature leg portion 113, and at its opposite end to a tie rod 114 which extends longitudinally of the preselector unit and is mounted in the end plates 21 and 22. Spring 111 holds the armature in its normal rest or open position against the tie rod 24 which is suitably cushioned. A pinion or idling gear 117, comprising a power-transmitting means, is freely rotatable on a pin 118 which is supported in the leg portion 113, the pinion 117 being positioned so as to be in continuous meshing engagement with the pinion 92. Movement of the armature through a distance defined by its angular movement between the pole piece 108 and cushioned tie rod 24 is sufficient to move the gear 117 into and out of engagement with the elongated pinion 44 which, as previously explained, is common to all of the control units 54.

Each armature 106 and its associated pinion 117 thus functions as a power-transmitting means for engaging one of the control units 54 with the elongated pinion 44 through the gear train or pinion gears 92 and 93. The pinions 92, 93, and 117 are always in continuous meshing engagement so that an immediate rotation of the gears 65 and 65' is obtained on engagement of the pinion 117 with the elongated pinion 44. A fibre washer 119 (Fig. 6) is mounted about the shaft 97 between the tie plate 101 and adjacent armature 106 to substantially eliminate any vibratory or chattering action of this armature from being transmitted into the frame means on operation of the magnet 109 in an A. C. sys-

tem. This vibration insulating means is the only one necessary in the entire assembly of the shaft 97 and its associated pinions 92 and armatures 106. The magnets 109 are mounted on a bracket member 123 (Fig. 1) so as to be substantially opposite their corresponding armatures 106. Member 123 is supported on the end plates 21 and 22 by suitable screw means 120 or the like. A terminal panel 124 is secured to the upper portion of the bracket 123 as viewed in Fig. 2, with the panel being suitably insulated from the bracket. Electrical connection of the magnets to the operating electrical system is thus directly made in immediate adjacency to the assembly position of the magnets in the preselector unit.

In the construction of the tuning apparatus or preselector unit as thus far described, it is seen that the shafts 97 and 104, and the magnet support 123, while forming component parts of the preselector unit, function also as tie rods in supporting the end plates 21 and 22 and thus coact with the tie rods 23 in providing a unit of simple and compact, but rugged design. It is seen also that the corresponding parts for each unit 54 are arranged longitudinally of the preselector unit while each control unit 54 and its component parts are arranged transversely of the preselector unit.

A relay unit 126 (Fig. 2) including operating magnets 127 and 128 for armatures 129 and 131, respectively, is included in the circuit of the magnets 109 and motor 26 and operates to control the starting and stopping of the radio receiving apparatus, as will be explained.

As shown in the circuit diagram in Fig. 8, the magnets 109 are arranged in parallel between conductors 132 and 133 which are inductively connected to a suitable supply source 134. The motor 26 which is in driving engagement with the elongated pinion 44, as was previously explained, is connected in series with each of the magnets 109 so as to be energized concurrently on energization of each magnet. It is thus seen that rotation of the elongated pinion 44 occurs simultaneously with the actuation of the power-transmitting means 106-117 by the magnet 109 so that selective operation of a control unit 54 is obtained immediately on closing a push button 135.

The radio "off" button or switch 136 is connected in parallel with the magnets 109 and is in series connection with the magnet 128. On actuation of the "off" switch to its closed position, the magnet 128 attracts the armature 131 into a locked position with an interlock member 137 so that this initial actuated position of the armature 131 is retained even after the "off" switch 136 is opened. The armature 131 (Figs. 2 and 8) is provided with an arm 138 which is engageable with contacts 139 and 141, the contact 139 controlling the circuit 142 to the radio heaters and the contact 141 the rectifying circuit 143. The radio "on" button or switch 144 is connected in parallel with the magnets 109 and with the "off" switch 136. Operation of the button 144 energizes the magnet 127 to release the interlocking member 137 from its engagement with the armature 131. This releasing of the armature 131 moves the contacts 139 and 141 in a direction to close the circuits to the radio heaters and rectifier so as to condition the radio receiving apparatus (not shown) for broadcast reception. The arrangement of the circuits shown in Fig. 8 is such that the set may also be turned on by pressing any of the tuning buttons as 135,

energizing magnet 109 and motor 26. The "on" coil 127 is connected in parallel with motor 26 in a switch leaf 139A whenever the set is off, and so receives energy whenever the motor is energized under this condition. As soon as the latch 137 is stopped and switch 139 moves to the "on" position, this circuit is broken and coil 127 is deenergized.

In the operation of the preselector unit let it be assumed that the "on" switch 144 has been turned on. On actuation of a push button 135, which may be located remotely from the tuning apparatus, the energizing circuit for a magnet 109 is closed through conductors 132 and 133 as is also the circuit of the motor 26 which is connected in series with the magnet. Concurrently with the start of operation of the motor 26 to rotate the elongated pinion 44 through clutch means 33 and gear 43, the gear 117 on the armature 106 is moved into engagement with the pinion 44. The motor 26 is of unidirectional type and the gear train from the motor to the elongated pinion 44 is arranged so that the pinion 44, as viewed in Fig. 2, rotates in a clockwise direction, which, in turn, rotates the power-transmitting gear 117 in a counter-clockwise direction. This direction of rotation of the pinion 44 acts to pull the gear 117 into meshing engagement with the elongated pinion so that the gear 117 is locked in mesh during the tuning operation. Since this meshing engagement holds the armature 106 in its attracted position against the magnet pole face 108, a mechanical pressure urging the armature toward the pole face occurs concurrently with the electrical attraction of the armature by the pole face to aid the magnet in operating the power-transmitting means 106-117. The magnets 109, therefore, need only be large enough to pull the armature 106 into its attracted position against the pole face 108. This utilization of the mechanical reaction between the gears 44 and 117 provides for the use of relatively small magnets 109, since the magnet merely functions as a tripping means to initially engage the gear 117 and the pinion 44; the pulling of the gear 117 into meshing engagement with the pinion 44 being sufficient to maintain the geared or interlocked engagement between such gears so long as the pinion is rotating. The floating or spring connection of the fibre gear 43 to the pinion shaft 45 assures a positive disengagement between the gears 44 and 117 on completion of a tuning operation. A torsional force is built up in the spring 50 so that when the motor 26 is deenergized the gears 44 and 117 are thrown out of mesh by the return of the spring 50 to its free untensioned position. The constantly applied mechanical pressure on the armature 106 by the operation of the gears 44 and 117 serves further to reduce the chattering action of the armature when the magnet 109 is operating in an A. C. system.

With the pinions 92 and 93 in continuous engagement with each other and with the pinion 92 in engagement also with the gear 117, the pinions 92 and 93 are reversely rotated so as to rotate their associated gears 65 and 65', respectively, in opposite directions on the control shaft 57. As the gears 65 and 65' are rotated, their respective projections 76 and 76', and the projections 73 and 74 on the washers 71 and 72, respectively, are moved into successive engagement in a stepped relation as is clearly shown in Fig. 1, and as was previously fully described. Since the

gears 65 and 65' are rotated in opposite directions, their coupled engagement with the projection 71 on the adjustable collar member 78 occurs on opposite portions of the projection 71. The gear first to be coupled with the projection 71 rotates the control shaft 57 by virtue of the fixed position of the collar member 78 on the shaft 57, until both gears are in coupled engagement with the member 78. Since the driving force of the gears 65 and 65' acts on the projection 71 in opposite directions and since these opposite forces are equal to each other, the coupled engagement of both gears with the member 78 will lock the gears against any further rotation thereof and hence of the control shaft 57. This locked engagement of the gears 65 and 65' with the member 78 defines the predetermined control position of the shaft 57 and hence of the condenser 63, which is in driven engagement with the shaft 57 through gears 58 and 61, as was previously explained. Although the rotation of the motor is unidirectional, the opposite rotation of the gears 65 and 65' provides for a rotation of the control shaft and hence of the condenser in either direction, the direction of rotation being dependent upon which gear 65 or 65' is first coupled to the adjustable member 78.

To adjust the various control units 54 to a predetermined control position, screw 87 in the thrust mechanism 88 is withdrawn until the center washers or adjustable collars 78 are free to turn relative to the shaft 57. Shaft 57 is then adjusted to a desired control position by a suitable manual control knob (not shown) for the frequency-changing means 63. With the shaft in this position, a unit 54 is operated to its locked position by pushing a button 135, while the operator holds the manual control knob and hence the shaft 57 from turning. The member 78 is thus adjusted to a predetermined control position of the shaft 57. A similar procedure is repeated for the other control units 54. During this setting operation, the members 78 are maintained in adjustment by virtue of the fact that their frictional engagement with the bushings 66 and 67 is sufficient to maintain their relative positions on the shaft 57. Spring washer 86 keeps all parts on shaft 57 always under pressure for this purpose. When all of the units 54 have been adjusted, the screw 87 is tightened whereby to frictionally lock all of the members 78 in fixed positions relative to the shaft 57.

It has been noted that three washers 71 and three washers 72 are used in each of the control units 54. The number of washers, however, may be changed in accordance with a particular tuning structure, a larger number of washers providing for an increased driving ratio between the control unit 54 and shaft 57. This driving ratio provides for a relative free motion of the gears 65 and 65', between their locked positions, which is commensurate to the driving ratio between the shaft 57 and condenser shaft 62. A free motion of this degree in each unit 54 conditions each unit to move the condenser through its complete tuning range, which, in the case of the usual gang condenser, is a movement of about 180°. It is readily apparent, therefore, that as the driving ratio between the rotary control shaft 57 and condenser 63 is increased, the accuracy of the control unit 54 in moving the shaft 57 to a predetermined control position is increased, since the error of tuning is decreased 75 in proportion to the increase in the driving ratio.

In other words, the angular displacement of the condenser 63 is only a predetermined portion of that of the shaft 57, for any tuning operation. In the embodiment of Fig. 1, a driving ratio of about 3½ : 1 between the shaft 57 and condenser 63 has been found to give very satisfactory tuning results. Where a connection such as a flexible cable is used as a mechanical transmission means between a control knob and a condenser, an appreciable angular displacement occurs in the cable so as to impair the precision of the tuning operation. In one commercial embodiment of the invention a driving ratio of 12 : 1 has been satisfactorily employed to reduce the degree of error in the tuning resulting from the use of a flexible cable.

From the foregoing it will be apparent that the described arrangement, embodying the present invention, includes a drive mechanism for a selector system. Preferably, the selector system is of the type which includes a plurality of control units or selectors 54 for individually and independently positioning a controlled element, such as shaft 57, to one of a plurality of pre-selected positions corresponding in number to the number of selectors. The driving mechanism for this preferred form of the invention comprises a common driving member for all of the selectors, this member being the elongated pinion 44. A plurality of independent driven elements, namely, the sets of pinions 92, 93, are provided for individually mechanically actuating different ones of the selectors 54 from driving member 44, but they normally have an interrupted driving connection between their associated selectors and the common driving member. The drive mechanism further includes a displaceable power-transmitting means, comprising the gears 117 in continuous meshing engagement with the driven elements 92, for selectively completing a driving connection between any of the selectors 54 and the common driving pinion 44 through the corresponding one of the driven elements 92, thereby selectively to actuate the selectors from the driving member 44.

While only one particular selector mechanism has been represented in the drawings, it will be understood that the invention is not limited to that single application. If desired, any of a variety of selectors may be actuated by the driving system disclosed herein. In applicant's Patent No. 2,411,617, several different selectors are shown and any of them may be operated from the driving system under consideration. It will also be understood that the power-transmitting gears 117 are subject to manual displacement where this method of operation is desirable.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. Electrical rotary control apparatus adapted to be operated to a predetermined stop position, including in combination rotary driving means, rotary driven means, stop means including rotary means therein operatively connected to said rotary driven means, and selectively operated power-transmitting means operatively connecting said rotary driving means and the stop means,

said power-transmitting means having rotary means therein to transmit the rotary motion of the driving means to the rotary means of the stop means to rotate the rotary driven means to a predetermined stop position.

2. Electrically driven rotary control mechanism including in combination rotary driving means, a rotary control unit adapted to be operated to a predetermined stop position, said control unit having a pair of reversible gears and stop means therebetween, rotatable driven means connected with said pair of gears in said control unit and of such structure as to provide reversible rotary movement for said gears, and power-transmitting means for said control unit selectively operated to selectively and operatively connect said rotary driving means with the rotatable driven means.

3. In electrical apparatus having a control shaft, means for reversely rotating said control shaft to a predetermined control position including a pair of rotatable portions freely rotatable on said shaft, a member on said shaft and connectable with said pair of rotatable portions in a shaft operating position, a pair of rotary driven portions connected for concurrent reversed rotation, with each of said driven portions being connected with a corresponding rotatable portion, a unidirectional rotary driving means, and selectively operable power-transmitting means having a rotary portion for connecting one of said driven portions with said driving means reversely to rotate said driven portions, with said rotatable portions being reversely rotated by said driven portions into a shaft operating position with said member.

4. In electric control apparatus having a rotary control shaft with a control member and a toothed member thereon with the latter member operatively connected with the former member in shaft operating position, the combination of driven gear means in continuous engagement with the toothed member, driving gear means, power-transmitting means movably mounted having a gear thereon in continuous meshing engagement with one of said two gear means, said power-transmitting means including a movable member supporting said gear thereon and movable to move said gear therewith into meshing engagement with the other of said two gear means intermeshingly to connect said two gear means to drive said driven gear means and the rotary control shaft therewith, and selectively operable means for operating said power-transmitting means.

5. In electric control apparatus having a rotary control shaft and a control member and a toothed member thereon with the latter member operatively connected with the former member in shaft operating position, the combination of rotary driven means in continuous meshing engagement with the toothed member, a motor driven driving gear, pivoted power-transmitting means having a gear thereon in continuous meshing engagement with said rotary driven means, and magnet means energizable to pivot the power-transmitting means and engage the gear thereon with the driving gear to drive the rotary control shaft.

6. Control apparatus having a control unit for positioning a controlled element to a predetermined control position comprising, rotary driven means in operative engagement with said control unit, a motor driven driving gear for said rotary driven means, a displaceable connector having

a rotary gear thereon, and actuating means for displacing said connector to engage the rotary gear thereon with said driving gear and said rotary driven means, said rotary and driving gears and said rotary driven means being arranged so that rotation of said driving gear in one direction operatively interlocks the driving gear and said rotary gear independently of a continued energization of said actuating means.

7. In control apparatus including in combination rotary driven means normally stationary until driven, rotary driving means including a rotating shaft, a driver mounted thereon, and resilient means operatively connecting said driver and said shaft, power-transmitting means movable into driving operative connection between said rotary driven means and said driving means upon application of an urging force thereon, with said rotary driving means interlocking said power-transmitting means in said driving operative connection, and said resilient means acting upon said rotating shaft upon completion of a driving operation by said shaft to disrupt said interlocking.

8. Electrically driven rotary control means having electric motive power including in combination a rotary shaft, a rotary control unit having adjustable means on said rotary shaft, toothed means including a pair of oppositely rotatable gears, and lost motion coupling means operatively connecting said adjustable means and said pair of oppositely rotatable gears, and means in the control unit acting on said lost motion coupling means, on said adjustable means, and on said oppositely rotatable gears to stop the rotary shaft at a predetermined position, and means for operatively connecting said oppositely rotatable gears with the electric motive power including a pair of intermeshed oppositely rotating pinion gears with each of said pinion gears meshed with a corresponding rotatable gear, driven means including a gear adapted to be driven by the electric motive power, and a selectively operable power-transmitting means having a gear thereon in meshing engagement with one of said pinion gears to thereby drive said pinion gears and transmit motive power to the control unit to operate the same to a predetermined position for the rotary shaft.

9. A drive mechanism for a selector system including a plurality of selectors for individually and independently positioning a controlled element to one of a plurality of preselected positions corresponding in number to the number of selectors comprising; a common rotary driving member for all of said selectors; a plurality of independent rotary driven elements for individually mechanically actuating different ones of said selectors from said driving member but normally having an interrupted driving connection between their associated selectors and said driving member; and displaceable power-transmitting means including at least one additional rotary member for selectively completing a driving connection between any of said selectors and said driving member through the corresponding one of said driven elements, thereby selectively to actuate said selectors from said driving member.

10. A drive mechanism for a selector system including a plurality of selectors for individually and independently positioning a controlled element to one of a plurality of preselected positions corresponding in number to the number of selectors comprising; a common rotary driving

member for all of said selectors; a plurality of independent rotary driven elements for individually mechanically actuating different ones of said selectors from said driving member but normally having an interrupted driving connection between their associated selectors and said driving member; and displaceable power-transmitting means including at least one additional rotary member for selectively completing a driving

5 connection between any of said selectors and said driving member through engagement with the peripheral portion of the corresponding one of said driven elements, thereby selectively to actuate said selectors from said driving member.

10 15. 11. A drive mechanism for a selector system including a plurality of selectors for individually and independently positioning a controlled element to one of a plurality of preselected positions corresponding in number to the number of selectors comprising: a common rotary driving

20 member for all of said selectors; a plurality of independent rotary driven elements for individually mechanically actuating different ones of said selectors from said driving member but normally having an interrupted driving connection between their associated selectors and said driving member; and a plurality of independently displaceable power-transmitting connectors individually including an additional rotary mem-

25 ber associated with different ones of said driven elements for selectively completing driving connections between said selectors and said driving member through said driven elements, thereby selectively to actuate said selectors from said

30 35. 35. 12. 12. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

40 45. 40. 45. 13. 13. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

50 55. 50. 55. 14. 14. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

56 60. 56. 60. 15. 15. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

65 70. 65. 70. 16. 16. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

75 80. 75. 80. 17. 17. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

85 90. 85. 90. 18. 18. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

95 100. 95. 100. 19. 19. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

105 110. 105. 110. 20. 20. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said

115 120. 115. 120. 21. 21. A drive mechanism for a selector system including a plurality of selectors for individually and independently positioning a controlled element to one of a plurality of preselected positions corresponding in number to the number of selectors comprising: a common rotary driving member for all of said

of said driven elements, thereby selectively to actuate said selectors from said driving member.

14. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven elements for individually mechanically actuating different ones of said selectors from said driving member but normally having an interrupted driving connection between their associated selectors and said driving member; and a plurality of pivotally supported and independently operable power-transmitting connectors individually including an additional rotary member for selectively completing a driving connection between any of said selectors and said driving member through the corresponding one of said driven elements, thereby selectively to actuate said selectors from said driving member.

15. A drive mechanism for a selector system including a plurality of selectors for individually and independently positioning a controlled element to one of a plurality of preselected positions corresponding in number to the number of selectors comprising: a common rotary driving member for all of said selectors; a plurality of independent rotary driven members for individually mechanically actuating different ones of said selectors from said driving member but normally disengaged from said driving member; and a corresponding plurality of selectively displaceable power-transmitting connectors individually including an additional rotary member for individually coupling any of said driven members with said driving member, each of said additional rotary members being in continuous engagement with one of said driven and driving members and being displaceable for concurrent engagement with the other of said members to effect a mechanical coupling therebetween, thereby selectively to actuate said selectors from said driving member.

16. A drive mechanism for a selector system including a plurality of selectors for individually and independently positioning a controlled element to one of a plurality of preselected posi-

5 tions corresponding in number to the number of selectors comprising: a unidirectionally rotatable common driving gear for all of said selectors; a plurality of independent driven gears for individually reversibly actuating different ones of said selectors from said driving gear but normally having an interrupted driving connection between their associated selectors and said driving gear; and displaceable power-transmitting 10 means including at least one additional gear for selectively completing a driving connection between any of said selectors and said driving gear through the corresponding one of said driven gears, thereby selectively to actuate said selectors from said driving gear.

15 17. A drive mechanism for a selector system including a plurality of longitudinally spaced selectors for individually and independently positioning a controlled element to one of a plurality of preselected positions corresponding in number to the number of selectors comprising: a common longitudinally extending rotary driving member for all of said selectors; a plurality of longitudinally spaced independent rotary driven elements for individually mechanically actuating different ones of said selectors from said driving member but normally disengaged from said driving member; and a corresponding plurality of power transmitting connectors individually including an additional rotary member in continuous engagement with different ones of said driven elements but selectively displaceable for concurrent engagement with said driving member for completing a driving connection between any of said selectors and said driving member through the corresponding one of said driven elements, thereby selectively to actuate said selectors from said driving member.
